UNITED STATES PATENT OFFICE.

STEPHEN I. FEKETE, OF DETROIT, MICHIGAN, ASSIGNEE TO HUDSON MOTOR CAR COMPANY, OF DETROIT, MICHIGAN, A CORPORATION OF MICHIGAN.

INTERNAL-COMBUSTION ENGINE.

1,173,105.

Specification of Letters Patent. Patented Feb. 22, 1916.

Application filed January 21, 1915. Serial No. 3,434.

To all whom it may concern:

Be it known that I, STEPHEN I. FEKETE, a citizen of the United States, residing at Detroit, county of Wayne, State of Michigan, have invented a certain new and useful Improvement in Internal-Combustion Engines, and declare the following to be a full, clear, and exact description of the same, such as will enable others skilled in the art to which it pertains to make and use the same, reference being had to the accompanying drawings, which form a part of this specification.

My invention relates to internal combustion engines and an object of my improvement is to provide an engine of improved construction particularly in reference to appearance, compactness, convenience of assembling, and accessibility.

20 In the accompanying drawings: Figure 1, is a central longitudinal sectional elevation of an engine embodying my invention. Fig. 2, is a section on the line B—B Fig. 1, looking from the left of said line. 25 Fig. 3, is an end elevation, the bottom being removed and various parts separated, to illustrate the construction and mode of assembly. Fig. 4, is a side elevation showing the main casting of the frame and one 30 of the cylinder castings and attached parts separated from the frame. Fig. 5, is a section on the line E—E Fig. 1 looking from the left of said line.

35 *a a* indicates the engine casing as a whole, and *b b* is the frame or main casting to which the other parts of the casing are secured.

c is the bottom, or oil pan, of the casing.

40 *d* is a cover extending over the portion of the frame between the cylinder casting and inclosing part of the mechanism.

e is a housing or extension from the casing *b* which extends over the fly wheel 40 and is extended laterally to form lugs, or 45 supports, *h h* for the engine.

f is a casing at one end of the frame or casting *b* inclosing some of the mechanism of the engine.

g, g indicate a pair of lateral extensions

at one end of the casting *b*, serving as lugs 50 to support the engine at this end while the lugs *h h* above described support the engine at the other end.

i j k are upwardly extending partitions formed integral with the frame or casting *b*.

n is a web formed in the arc of a circle in cross section, as shown in Figs. 2 and 5 and extending between the lower ends of the end partitions *i* and *k*.

o p are end, and *m² m²* are side, walls integral with the casting *b* and forming the vertical walls of the crank case below the web *n*.

m is a central partition extending downward from the central part of the web *n* and formed integral with the side walls of the crank case.

q, r and *s* are bearings formed respectively in the partitions *i, j* and *k*, the bearing *q* is adapted to receive and hold the dynamo 18 and the bearings *r* and *s* are adapted to receive the arbors of the shaft 16 which rotates therein.

t u v are bearings formed, respectively, in the end wall *o*, the central wall *m* and the end wall *p* of the crank case. The main shaft 11 rests and is adapted to turn in the bearings *t u v*.

w x y are bearings in the upper ends of the partitions *i, j, k* in which bearings the 38 cam shaft 19 rotates. The main frame *b b* is a single integral aluminum casting and it is faced off along its lower edges 2, 3, along the upper edges of the side walls *m² m²* at 4, along the tops of the partitions *i j k* and *s* along the edges of said partitions as indicated at 7 and 8.

5 is an extended faced-off edge of the web *n* at the sides of said web.

9, is a shelf or platform adapted to receive the lighting magneto or dynamo.

10—10 are bearings in which the shaft for the lighting magneto may turn. This shaft is indicated at 13, Fig. 1. It extends transversely across the frame and has a gear wheel thereon which is engaged by a gear wheel 12 on the crank shaft 11.

14, is a chain extending over sprocket

wheels on the shafts 11 and 16, so as to transmit rotary motion from the shaft 11 to the shaft 16.

15, is a fan upon the shaft 16.

5 20, is a chain extending over sprocket wheels on the shaft 16 and on the cam shaft 19. The sprocket wheels uniting the shafts 11, 16 and 20 are of such relative diameters and so arranged that the cam 19 shall have 10 the proper angular position and speed of rotation relative to the shaft 11.

22—22 are iron castings in which are formed the cylinders 21, the cored out water passages 36—37, the intake manifold 29, 15 the intake ports 28, the exhaust valve ports 32 and the exhaust passages 30.

The cylinders 21 are formed in angular positions shown and are open at their upper and lower ends. The castings 22 are machined along a surface 22^a which is at the 20 angle shown to the axis of the cylinders 21, the cylinders open at their upper ends through such surface, and the valve ports 28—32 are directly opposite the openings 25 through these surfaces so that when the covers to the cylinder are removed the valves and valve seats are easily accessible.

25, indicates covers, cored out for water passages as shown and provided with screw 30 threaded apertures 29 to receive the spark plugs. The covers 25 fit against the surface 22^a and are bolted thereto to cover the cylinders. The castings 22—22 are finished off along their faces 23—24 at right angles 35 to each other and fit against the side edges of the upwardly extending partitions *i j k* and the upper edges 4 of the side walls *m*² and the upper edges of the end walls *o p* and are secured in this position by bolts, as 40 shown in Figs. 2 and 3.

26—26 are the valves, the stems of which extend inwardly toward each other and are acted on by the cams on the shaft 19, as indicated most distinctly in Fig. 2. This 45 valve construction is particularly described and claimed in a copending application filed January 21, 1915, Serial No. 3435 of 1915.

The exhaust passages 30 open through the flat horizontal upper surfaces of the 50 casting 22—22 and cast aluminum manifolds 27—27 are secured by bolts on said surface so that the passages 30 shall open into said manifold. The bottom, or oil, pan *c* is secured to the lower edges 2, 3 of the 55 walls *m*² and together with said walls form the inclosed crank case. An air pump may be mounted upon the front of the frame *b* as shown and means provided to removably couple said pump to the shaft 19. By this 60 means facilities are afforded for inflating the tires. The fly wheel may be provided with peripheral gear teeth and gearing provided for coupling the dyna-motor 18 thereto for starting the engine.

What I claim is:

1. The combination of a frame, a cylinder casting secured at its side to the side of said frame and provided with a valve port, a valve upon said port having a stem, a cam shaft carried by said frame, said valve stem extending into position to be actuated by a cam on said shaft, said cylinder casting being provided with a surface extending outward and downward at an angle to the axial line of said port and the cylinder of said casting, said cylinder opening through said surface adjacent to said port, said casting being provided with a second surface above the first named surface and with an exhaust passage leading from said cylinder and opening through said second surface, a manifold secured on said second surface and a cover secured on said first mentioned surface. 65 70 75 80

2. In an engine, the combination of a frame having an upright, a cylinder casting adapted to be secured at its side to one side of said upright, a cylinder casting adapted to be secured at its side to the other side of said upright, cylinders formed in 90 said castings and having their axes converging toward a point below said cylinders, valves in said cylinders extending therefrom, and a cam shaft located upon said upright between said cylinders, said 95 valves extending into a position to be actuated by said cam shaft.

3. In an engine, the combination of a frame having an upright, a cylinder casting adapted to be secured to one side of said 100 upright, a cylinder casting adapted to be secured to the other side of said upright, cylinders formed in said castings and having their axes converging toward a point below said cylinders, valves in said cylinders, and a cam shaft located upon said 105 upright between said cylinders and adapted to actuate said valves, said castings being provided with surfaces extending at an angle to the axes of said cylinders and said 110 valves, said cylinders opening through said surfaces adjacent to said valves, said valves extending into position to be actuated by said cam shaft.

4. In an engine, the combination of a frame having an upright, a cylinder casting adapted to be secured to one side of said 115 upright, a cylinder casting adapted to be secured to the other side of said upright, cylinders formed in said castings and having their axes converging toward a point below said cylinders, valves in said cylinders, and a cam shaft located upon said 120 upright between said cylinders and adapted to actuate said valves, said castings being provided with surfaces extending at an angle to the axes of said cylinders and said 125 valves, said cylinders opening through said

surfaces adjacent to said valves, each of said castings being provided with a second surface above the first named surface and with exhaust passages opening through 5 said second surface, manifolds secured upon said second surface so that said exhaust passages shall open into said manifolds and covers for closing the openings in said first mentioned surfaces, said valves extending 10 into position to be actuated by said cam shaft.

5. In an engine, the combination of a frame consisting of uprights having vertical edges, said frame also having horizontal 15 edges extending from the lower ends of the edges of said uprights, cylinder castings adapted to fit against said upright and horizontal edges and be secured thereto, the cylinders extending slantingly through said 20 castings.

6. In an engine, the combination of a frame consisting of uprights having vertical edges, said frame also having horizontal edges extending from the lower ends of the 25 edges of said uprights, cylinder castings adapted to fit against said uprights and horizontal edges and be secured thereto, the cylinders extending slantingly through said 30 castings, the lower part of said frame being formed to constitute a part of the crank case.

7. In an engine, the combination of a frame consisting of uprights having vertical edges, said frame also having horizontal 35 edges extending from the lower ends of the edges of said uprights, cylinder castings adapted to fit against said uprights and horizontal edges and be secured thereto, the cylinders extending slantingly through said 40 castings, the lower part of said frame being formed to constitute a part of the crank case, and operating mechanism located on said uprights between said castings.

8. In an engine, the combination of a frame consisting of uprights having vertical edges, said frame also having horizontal edges extending from the lower ends of the edges of said uprights, cylinder castings adapted to fit against said uprights and 50 horizontal edges and be secured thereto, the cylinders extending slantingly through said castings, the lower part of said frame being formed to constitute a part of the crank case, operating mechanism located on 55 said upright between said castings, and a partition n between said operating mechanism and the crank case of the engine.

9. In an engine, a cylinder-casting having a surface cutting the bore of said cylinder at an angle other than a right angle to the axis thereof so as to form an opening through which the piston may be removed, said casting being provided with a valve 60 port located in a side wall of the cylinder

opposite the opening formed by the cutting- 65 away of the side wall of said cylinder by said surface.

10. In an engine, a cylinder casting having a surface cutting the bore of said cylinder at an angle to the axis thereof so as to 70 form an opening through which the piston may be removed, said casting being provided with a valve port located in a side wall of said cylinder opposite the opening of the cylinder bore through said surface, 75 a removable cover for said opening, said casting being provided with an exhaust port opening through the surface of said casting above said opening and an exhaust passage adapted to be secured to the surface of said 80 casting so that it shall communicate with said exhaust port.

11. A frame of cast aluminum having end uprights and a portion below said uprights of greater lateral extent than said uprights, 85 and cylinder castings secured to said uprights and extended portion of the frame.

12. In an engine, a frame, cylinder castings adapted to be secured at their sides to opposite sides of said frame, a cam shaft 90 located on said frame between said castings, the opposite cylinders of said castings converging toward each other, a valve in a side cylinder wall of each of said castings extending at a relatively wide angle from the 95 axis of said cylinder and into position to be actuated by said cam shaft.

13. In an engine, a cylinder having an end surface cutting the bore of said cylinder at an angle other than a right angle to the 100 axis thereof so as to form an opening through which the piston may be removed, a valve located in a side wall of said cylinder opposite the opening formed by the cutting-away of the side wall of said cylinder 105 by said surface.

14. In an engine, the combination of a cylinder having an end surface cutting the bore thereof at an angle to its axis so as to form an opening through which the piston 110 may be removed, a second surface located above the first named surface, exhaust openings through said second surface, a manifold adapted to be secured on said second surface communicating with the exhaust 115 openings, and a cover removably secured on the first named surface to close the openings of the bore of the cylinder.

15. In an engine, the combination of a frame, a cylinder casting interfitting at its 120 side with the side of said frame, a cam shaft carried by said frame, a valve stem extending from said casting into position to be directly actuated by the cams on said shaft, said cylinder casting being provided with a 125 surface extending outward and downward at an angle to the axial line of said valve, said cylinder opening through said surface

adjacent to said valve, said casting being provided with a port adapted to said valve.

16. A frame having end uprights, and a portion below said uprights of greater lateral extent than said uprights, and cylinder castings adapted to be secured to said uprights and extended portion of the frame.

17. In an engine, a frame, and cylinder castings adapted to be secured at their sides to opposite sides of said frame, a cam shaft located on said frame between said castings,

a valve in a side wall of a cylinder in each of said castings extending at a relatively wide angle from the axis of said cylinder and into position to be actuated by said cam shaft.

In testimony whereof, I sign this specification in the presence of two witnesses.

STEPHEN I. FEKETE.
